E. C. SHAFER

TABLE I

Filed Jan. 25, 1926

Inventor.
Edward C. Shafer
By
R. S. Berry
Attorney.

UNITED STATES PATENT OFFICE.

EDWARD C. SHAFER, OF SANTA MONICA, CALIFORNIA.

TABLE.

Application filed January 25, 1926. Serial No. 83,450.

This invention particularly pertains to a table or stand of the class adapted to be positioned astride the limbs or body of a person sitting or reclining on a bed, couch or the 5 like, and has as its primary object the provision of a structure of the above character which is adapted to be supported on a bed and used as a carrier for trays and similar objects.

Another object is to provide a stand embodying an open frame construction so formed as to be light in weight in proportion to its size to facilitate handling thereof and which is so formed as to be strong and 15 durable.

Another object is to provide a bed stand which may be formed in most part of hollow metal tubing and so constructed that it may be readily assembled and economically manufactured.

A further object is to provide a means in a stand of the above character for effecting detachable clamping engagement with a tray or panel supported thereon whereby such 25 tray or panel may be securely held against displacement under ordinary tilting movement to which the stand may be subjected when in use, and which clamping means is adaptable for engagement with trays or 30 panels of various dimensions.

With the foregoing objects in view, together with such other objects and advantages as may subsequently appear, the invention resides generally in providing a stand 35 having a top comprising an open frame construction including adjustable clamps adapted to be detachably engaged with trays or panels resting on the stand top.

The invention further resides in the parts, 40 and in the combination, construction and arrangement of parts hereinafter described and claimed and illustrated by way of example in the accompanying drawing, in which:—

Fig. 1 is a perspective view of the stand illustrating the manner in which a tray may 45 be supported thereon;

Fig. 2 is a view of the stand as seen in longitudinal section;

Fig. 3 is a detail in horizontal section 50 through a corner portion of the top frame;

Fig. 4 is a detail in vertical section as seen on the line 4—4 of Fig. 3;

Fig. 5 is a detail in section as seen on the line 5—5 of Fig. 1;

Fig. 6 is a detail in perspective illustrat-

ing the manner of effecting connection between a series of cross rods at the central portion of the stand top;

Fig. 7 is a perspective view of one of the clamping members;

Fig. 8 is a plan view of one of the clamping members with portions broken away.

Referring to the drawings more specifically, 10 indicates a rail constituting the marginal frame portion of the stand top 65 which rail is preferably formed of metal tubing and is here shown as bent to form a frame of substantially rectangular form including side members 11 and 12 and end members 13 and 14; the terminal portions 70 of the tubular rail 10 being connected together as shown in Fig. 5 by means of a short bar 15 over the end portions of which the terminals of the tubing are telescoped and affixed as by welding or brazing. 75

Legs 16 are provided at the corners of the frame and comprise comparatively short lengths of metal tubing fitted with feet 17 composed of knobs. The upper ends of the legs are inserted through openings 18 in the 80 rail 10, as shown in Figs. 3 and 4 and are secured to the rails by a welded or brazed joint 19 around the margin of the opening 18.

Extending longitudinally of the stand top 85 frame intermediate the side rails 11 and 12 and affixed at its ends to the end rails 13 and 14 is a rod 20 the opposite side faces of which are flat and parallel. The upper edge of the rod is recessed intermediate the ends 90 thereof to receive a horizontal plate member 21. The ends of the rod 20 extend through openings on the inner faces of the end rails 13 and 14 and are secured to the latter by welding or brazing. 95

Diagonal brace rods 22 formed of metal tubing of circular cross section extend from opposite corners of the rail and connect with the plate as particularly shown in Fig. 6. The outer ends of the diagonal rods 22 are 100 inserted through openings 26 in the rail 10 into engagement with the upper end portions of the legs 16, the latter being cut away as indicated at 28 to receive the end portions of the diagonal rods and extend astride the 105 latter thus affording an anchorage for the legs within the tubular rail serving to stabilize the connection between the legs and rail and affording a strong and substantial mounting for the legs. The diagonal rods 110

may be secured to the rail 10 by a weld or brazed joint 29 formed around the margin of the opening 26.

Transverse tubular rods 30 connect with the side rails 11 and 12 and with the plate 21, their outer ends extending through openings in the side rail and being secured in place by welding or brazing said rod 30 together with the diagonal rod 22 cooperate 10 with the longitudinal rod 20 to form a spider which has a flat top adapted to form a level support for a tray.

The plate 21 is formed with a series of marginal projections 31 of segmental cross section which are inserted within the inner open ends of the tubular rods 22 and 30 and to which the latter may be firmly secured by welding or brazing. The top surface of the plate 21 extends substantially flush with 15 the top surface of the rod 20 and in order that the tubular rods 22 and 30 may extend with their upper portions on a plane with the top surface of the plate 21 the segmental projections 31 are formed with their uppermost portions extending on a plane below the top surface of the plate 21 a distance substantially corresponding to the thickness of the walls of the tubular rods. The stand top is thus formed of a frame of open construction, which, by the arrangement of the rods shown is thoroughly braced and because of its open construction is extremely light in weight in relation to its size, and is designed to serve as a support for a removable 20 tray or panel as indicated by the dotted lines C in Fig. 1.

As a means for holding the tray against displacement or accidental shifting when positioned on the stand top, a pair of clamping members 32 and 33 are provided which are here shown as slidably supported on the longitudinal rod 20 for independent movement relatively to each other to permit their being disposed at various positions on the bar to accommodate trays of various sizes. The clamping members are here shown as comprising a U-shaped plate, the legs of which are formed with openings 35 through which the rod 20 extends to afford a slidable 45 connection between the plate and the rod. The rod and the openings 35 being rectangular, the slide plate is held against turning movement on the rod.

Carried by each of the slide plates is a 50 spring-pressed clamping finger 36 which is adapted to be engaged with the margin of a tray to clamp the latter against movement on the frame; and which clamping finger is here shown as embodying a pair of bent wires 55 having stem portions 37 extending downwardly through the top portion of the slide plate and projecting on opposite sides of the bar 20. The lower end portions of the stems 37 are connected together beneath the bar 20 by a transverse plate 38. Springs 39

bear between the plate 38 and the top portion of the slide plate and exert a downward pull on the stems 37 which are vertically slidable and thereby impart a downward pull on the fingers 36; the latter being 70 formed by continuations of the stems 37 turned substantially at right angles thereto and extending in parallel relation with their outer ends 40 turned inwardly toward each other, as shown in Fig. 8. The parallel 75 members are covered and connected together by means of a flexible tubing 41 which constitutes a cushion; the tubing being put in place by slipping its end portions over the spaced inturned terminations of the wire 80 which construction permits ready removal and replacement of the tubing 41.

In employing the stand the clamps 32 and 33 are normally disposed in such spaced relation as to permit the positioning of a tray 85 C therebetween, which is ordinarily effected after the stand has been placed in position on a bed astride the occupant thereof. The clamping fingers are elevated to a position above the plane of the rim of the tray by 90 pressing the bars 38 upwardly, whereupon the slide plates are moved inwardly against the opposite edges of the tray and the bar 38 released so that the fingers 36 will be 95 brought into engagement with the tray under the urge of the springs 39. The tray on being engaged by the fingers will be securely held against sliding movement on the stand top.

While I have shown and described a 100 specific embodiment of the invention, I do not limit myself to the exact details of construction or arrangement shown, but may employ such changes and modifications as come within the spirit and scope of the appended claims.

I claim:

1. In a stand of the character described, a marginal rail, a longitudinal rod carried by said rail, a plate intermediate the ends of said rod, a series of marginal projections on said plate, and tubular rods having their inner ends encompassing said projections and having their outer ends connected with said marginal rail.

2. In a stand of the character described, a marginal rail, a longitudinal rod carried by said rail, a plate seating on said rod intermediate its ends, a series of segmental projections on the margin of said plate the upper portions of which are depressed below the plane of the top surface of said plate, and a series of tubular rods the inner ends of which encompass said projections and the outer ends of which are affixed to said rail.

3. A stand of the class described comprising a top defining frame, legs connected to and supporting said frame, a rod connected with and extending between opposed points

of the frame, a plate mounted upon said rod having its upper face substantially flush with the upper surface of said rod, a plurality of rods in radial arrangement having 5 their outer ends secured to said top defining frame, and connecting means on said plate for securing together the inner ends of said rods with their tops flush with the top of the plate.

10 4. A table comprising a top defining frame, a longitudinal rod connected with and extending between opposed points of

said frame, other rods cooperating with said rod to form a spider, adapted to support a tray, and a clamp adjustable along said longitudinal rod, said clamp being adapted to retain a tray in adjusted position upon said spider, said longitudinal rod affording an unobstructed travel for said clamp from points near the mid-length of said rod to points 15 near each end thereof.

In testimony whereof, I have affixed my signature.

EDWARD C. SHAFFER.
